ASSIGNORS TO THE ACME TOBACCO COMPANY, A CORPORATION OF
MAINE.

CIGAR-FILLER-CUTTING MACHINE.

No. 843,927.

Specification of Letters Patent.

Patented Feb. 12, 1907.

Application filed March 22, 1906. Serial No. 307,525.

To all whom it may concern:

Be it known that we, RICHARD A. BRIGHT and ARTHUR W. DAVIS, both citizens of the United States, residing at Cranston, in the 5 county of Providence and State of Rhode Island, have invented certain new and useful Improvements in Cigar-Filler-Cutting Machines, of which the following is a specification, reference being had therein to the accompanying drawings.

Our invention relates to mechanisms for trimming tobacco-filler strips intended for subsequent employment in the manufacture of cigars, and has for its primary object the 15 production of filler-strips of such form, shape, and consistency as to facilitate their subsequent use in cigars, particularly in such cigars as those having a perfecto shape.

Our invention consists in imparting a vertically-inclined shape to the opposite extremities of a bunch of filler-strips and in employing for such purpose a knife, knives, or blades mounted at a vertical inclination to the plane over which horizontally-disposed 25 filler-strips are forced against the knife-edges.

A further feature of the invention is the provision of means for vertically pressing the strips prior to the cutting step or operation, 30 whereby the cross-sectional form and the density of the ultimate cigars is modified.

Novel provision is also made for delivering the cut strips from the knife advantageously arranged for subsequent manipulations.

35 Other novel features will be hereinafter set forth in the description and claims.

In the accompanying drawings, which form a part of this specification, Figure 1 is a front elevation of a form of machine which 40 embodies our invention; Fig. 2, a side elevation, partially in section, of the same; Fig. 3, a longitudinal section of the same on line xx of Fig. 4; Fig. 4, a plan view of the same; Fig. 5, a detail of the knife or blade members; Fig. 6, a detail of a modified form of cutting 45 member, and Fig. 7 a perspective view of a bunch of filler-strips after the cutting or shearing operation.

Like reference characters indicate like 50 parts throughout the views.

The frame 1 of the machine may be of any form of construction suitable for carrying the several details of mechanism. In the form 55 thereof herein shown it supports a base or guide plate 2, provided with elongated openings or slots 3 to receive the guides 4 of a

slide 5, to whose margin is fixed a block 6, preferably of wood; but this block may obviously be an integral part of the slide, since its purpose is merely to prevent dulling the 60 knives, whose relation with the slide will be later explained. The slide 5 is outwardly pressed by any desired means, a convenient form consisting of a retractile spring 7, whose extremities are fixed in the slide and 65 frame. The slide may be forced inwardly by any suitable means. A convenient mechanism for this purpose comprises a longitudinally-toothed bar or rack 8 upon the under surface of the slide, which is engaged and actuated by a segmental gear 9 on a crank-shaft 10, mounted transversely in the table, and whose arm 11 is connected by a rod 12 to a pedal 13, pivoted to the frame. A spring 14 upon the frame engaging the pedal forces the 75 latter upwardly.

Upright bearings 15, formed, preferably, integral with the base-plate 2, are joined by a vertical transverse plate 16, which together constitute a yoke or head 17 to support the 80 plunger and its actuating parts. The latter comprise, preferably, a rock-shaft 18, whose arm 19 is connected by a rod 20 to a pedal 21, mounted in the frame. The arm and pedal are normally held in elevated position 85 by a retractile spring 22, connecting the rod 20 with the frame. The yoke 17 supports a vertical guide 24, which has a face-plate 25, provided with a vertical oblong slot 26. In the guide-slides is a plunger 27, whose lower 90 end carries a horizontal presser-plate 28. The plunger is connected by a screw 29, traversing the slot 26, to a cross-bar 30, pivotally mounted in oblong slots 30' in the free ends of arms 31, fixed to the rock-shaft 18. 95

In order to adjustably limit the downward travel of the plunger 27 any convenient stop may be employed. For this purpose, however, we prefer to use an upright plate 32 upon the yoke 17, adjustable vertically by 100 means of suitable bolt-and-slot connections, (indicated in a general way by 33.)

For the purpose of directing the sheared strips from the cutter we employ a horizontal guide-plate 34, preferably mounted 105 upon the yoke and in this instance connected thereto through a flange or arm 35 by a screw 36.

The base-plate 2 below the plunger 27 is preferably depressed, thereby forming a 110 transverse shoulder 40. With their margins adjacent the shoulder 40 are fixed the ends

41 of the knife, knives, or blades 42, having their cutting edge or edges 43 toward the slide 5. In the preferred form of knife (shown in Fig. 5) the ends or bases 41 of the 5 knives or blades are provided with longitudinal slots 44, through which pass into the base-plate 2 screws 45, by which slot-and-screw arrangement the upwardly-inclined cutting-blades 42 are longitudinally adjustable to impart the character of cut desired in any particular class of cigars. The modified form of knife (shown in Fig. 6) may, if desired, be substituted for the one described and differs from the latter in that the blade 15 42' is in one piece, and therefore not separably adjustable. The cutting edge 43' is inclined to the plane of the base-plate *a*, which is the essential and characteristic feature of this invention. It is obvious that, if 20 desired, the ends 41' may be omitted and the knife be mounted by friction or other engagement with the yoke of the machine.

The operation of the machine described is as follows: The operator inserts a bunch of 25 filler-strips upon the plate 2 transversely thereof and beneath the presser-plate 28. The latter is then forced downwardly by the actuation of pedal 21, which impulse is communicated through the rod 20, arm 19, shaft 30 18, arms 31, bar 30, and plunger 27. The plate 28 compresses the strips to the required density of the particular case, the degree of compression being regulated by the vertical adjustment of the stop 32. The 35 slide 5 is next impelled toward the knife against the force of the spring 7 by depressing the pedal 13, which through the rod 12, arm 11, shaft 12, and segment-gear 9 impels the wooden block or facing 6 against the 40 compressed filler-strips with such force as to drive the blades 42 of the knife through the strips and impart to the latter the form illustrated in Fig. 7, wherein is indicated the cut product 46 and the severed portions 47. 45 The insertion of successive bunches of filler-strips forces the strips already trimmed along beneath the guide-plate 34.

What we claim is—

1. In a machine of the character described 50 the combination with the base-plate, of an inclined cutting-blade mounted upon the base-plate, a slide mounted upon the base-plate movable toward and from the blade, and means for moving the slide.

2. In a machine of the character described 55 the combination with a stationary inclined cutting-blade adapted to operate upon filler-strips, of a slide adapted to press the strips against the blade, and means for reciprocating the slide.

3. In a machine of the character described 60 the combination with the base-plate, of an inclined cutting-blade mounted upon the base-plate, a slide upon the base-plate mov-

able toward and from the blade, means for reciprocating the presser-plate, and means for actuating the slide.

4. In a machine of the character described 70 the combination with a stationary inclined cutting-blade adapted to operate upon filler-strips, of means adjacent the blade for compressing the strips, a slide adapted to press the compressed strips against the blade, and means for actuating the slide.

5. In a machine of the character described 75 the combination with the frame, of a cutting-blade fixed to the frame, a slide movable toward and from the blade mounted upon the frame in horizontal alinement with the blade, 80 a rack upon the slide, a crank-shaft in the frame below the slide, a segmental gear upon the shaft and engaging the rack, an arm upon the shaft, a pedal mounted in the frame, a rod connecting the arm and pedal, and spring 85 means upon the frame for forcing the slide away from the blade.

6. In a machine of the character described 90 the combination with the base-plate, of an inclined cutting-blade mounted upon the base-plate, a presser-plate adjacent the blade, means for limiting the travel of the presser-plate, a slide upon the base-plate movable toward and from the blade, means for reciprocating the presser-plate, and means for actuating the slide.

7. In a machine of the character described 95 the combination with two upwardly and inwardly inclined cutting-blades adapted to operate upon filler-strips, of a slide adapted to 100 press the strips against the blades, means for actuating the slide, and means intermediate the blades for guiding the cut filler-strips.

8. In a machine of the character described 105 the combination with the base-plate, of two upwardly and inwardly inclined cutting-blades mounted upon the base-plate, a vertically-movable presser-plate adjacent the blades, a horizontal guide-plate intermediate the blades and above the base-plate, a reciprocating slide upon the base-plate movable toward and from the blades, and means for actuating the slide.

9. In a machine of the character described 115 the combination with a stationary cutting-blade adapted to operate upon filler-strips said blade being inclined longitudinally of the strips and means for pressing the strips against the blade.

10. In a machine of the character described 120 the combination with a plurality of inclined cutting-blades adapted to operate upon filler-strips, means for adjusting the cutting-blades toward and away from each other, and means for pressing the strips 125 against the blades.

11. In a machine of the character described 130 the combination with the frame-yoke and base-plate, of a rock-shaft mounted in the yoke, arms upon the shaft, a cross-bar

supported by the arms, a guide upon the yoke, a plunger in the guide and fixed to the cross-bar, a presser-plate upon the end of the plunger, a lever-arm upon the rock-shaft, a 5 pedal upon the frame, a rod connecting the pedal and lever-arm, and means for elevating the connecting-rod.

In testimony whereof we have affixed our signatures in presence of two witnesses.
